EYELASH CURLER

Herman Bernstein, Brooklyn, N. Y.

Application January 29, 1941, Serial No. 376,430

11 Claims. (Cl. 132—32)

This invention relates to eyelash curlers and is an improvement over my prior Patent #2,214,318, dated September 10, 1940 for Eyelash curler.

In my said prior patent, I have disclosed an eyelash curler in which most of the parts are made of sheet metal, the operating arms being of spring material. Furthermore, the construction of my prior patent has certain peculiar movements which are not as simple as those of the present invention, and said construction also requires that the fingers of the user be positioned in front of the eye during the curling operation with consequent partial obstruction of vision.

The present invention therefore contemplates the provision of a comparatively simple eyelash curler made substantially entirely of sheet metal and easily operated, but utilizing the spring backed rubber member shown in my prior patent.

The present invention further contemplates the provision of a curler having a comparatively simple motion permitting the exertion of considerable pressure upon the cooperating jaws to effect the curling operation quickly and without danger of cutting or severing the hairs of the eyelashes, the parts being sufficiently yieldable inherently and by reason of their form and mounting to take up any excess pressure within the device without danger of injury or breakage.

The invention further contemplates the provision of means for adequately supporting the yieldable curling insert for one of the jaws of the device so that danger of cutting the hairs is minimized.

The various objects of the invention will be clear from the description which follows and from the drawing, in which,

Fig. 1 is a side elevation of the curler showing in dash-dot lines the positions assumed by the lower jaw and its operating handle mechanism prior to the insertion of the eyelash between the jaws.

Fig. 2 is a front elevation of the same.

Fig. 3 is a top plan view of the lower jaw.

Fig. 4 is a vertical section of the jaws taken on the line 4—4 of Fig. 2.

In the practical embodiment of the invention shown by way of example, the curler consists generally of the respective upper or fixed jaw 10, the lower or movable jaw 11, comparatively simple means to reciprocate the lower jaw toward and from the fixed jaw to press the eyelash therebetween, and a yieldable insert consisting of a spring backed strip of rubber removably arranged in the lower jaw and of the type de-

scribed and shown in my said prior patent. The fixed jaw 10 constitutes the upper transverse member of the frame 12 of polygonal shape, said frame being formed integrally with the elongated extension or arm 13 terminating at its lower end in the integral finger loop 14.

The parts 10, 12, 13 and 14 are all suitably stamped and bent from a single piece of comparatively thin sheet metal preferably spring metal, whereby the parts may yield to a certain extent when excess pressure is put thereupon so that the pressure upon the eyelash does not become excessive. The upper jaw therefore is comparatively wide throughout the greater portion of its length so as to be comparatively rigid during the curling operation and under normal pressures, but at its extremities said upper or fixed jaw is reduced in width at its juncture with the adjacent depending members 17, 18 of the frame 12 to leave comparatively narrow connecting members as 19 between the ends of the upper jaw and the frame members 17, 18, and formed by the recesses 15, 16. At their lower ends the depending members 17, 18 are joined by inclined members as 20, 21 to the lower transverse member 22 of the frame 12. The members 17, 18, 20 and 21 are made narrower than the jaw 10, whereby not only may the jaw yield relatively to the side members 17 and 18 by reason of the reduced connecting parts 19, but the entire frame may also yield to some extent relatively to its arm 13 under excess pressure put thereupon.

It will be noted, as best seen in Fig. 1, that the extension or arm 13 projects upwardly as at 23 beyond the frame member 22 into the space 24 inside of the frame 12 to some extent. The projection 23 is provided with a longitudinally arranged guide slot 25. A similar slot 25' is provided in the arm 13 considerably below the slot 25, said slots being substantially parallel and in substantial alignment. Outstanding at substantially right angles from the respective side edges of the arm 13 are the reinforcing flanges 26, 27 which aid in imparting rigidity to said arm and may also serve, as will be later explained in detail, to guide the lower jaw in its reciprocatory movement.

Said lower jaw is preferably somewhat narrower than the upper jaw, both being made convex outwardly, however, in the customary manner. The lower jaw is joined by the inclined frame members 28, 29 to the lower transverse member 30 to form a jaw frame, similar to the upper jaw frame 12, capable of slight distortion

under excess pressures in the manner above described in connection with the frame 12. Depending from the cross member 30 of the lower jaw frame is the integral extension or arm 31, whereby the lower jaw, its frame and said arm may be stamped, pressed and bent from a single piece of comparatively thin spring sheet metal. The arm 31 is inserted between the flanges 26 and 27 of the arm 13 and in face to face relation with said arm and reciprocates vertically therebetween as viewed in Figs. 1 and 2 to carry the lower jaw toward and from the upper jaw. To constrain the lower jaw to move in the desired straight line path, the extension 31 carries the spaced pins 32 and 33 passing through the respective slots 25 and 25' of the arm 13. Said pins are each headed as shown to prevent separation of the arms 13 and 31 from each other.

As has been hereinbefore indicated, suitable means are provided to move the lower jaw. As shown, said means comprises the bell-crank-lever 35, preferably made of thin spring sheet metal and provided at one end with the finger loop 36. Said lever is pivotally supported as by means of the pivot pin 37 passing through the supporting lug 38 outstanding at substantially right angles from an edge of the arm 13. The outer end of said lug is spaced a sufficient distance from the arms 13 and 31 to provide a crank arm 39 on the bell-crank-lever of sufficient length to impart the desired stroke to the movable arm 31 operating the lower jaw.

Outstanding integrally from an edge of said arm 31 and adjacent to and substantially parallel to the lug 38 is the apertured lug 40 provided with the opening or slot 41 into which is inserted the operating end part 42 bent from the lever portion 39. Said end part 42 is preferably of reduced width compared to that of the crank arm 39, but is nevertheless of sufficient strength to impart the required pressure to the lug 40 as the bell-crank-lever 35 is swung about its pivot in the proper direction to press the lower jaw 11 against the upper jaw 10. It will be noted that the finger loops 14 and 36 are below the eye and do not interfere with vision during the curling operation and that the user can also see through the interior of the frames of the jaws.

The lower jaw is provided with a series of comparatively short, spaced and inwardly directed lugs 45 at substantially right angles to the face of said jaw and on which the removable yieldable member 46 forming part of the lower jaw may rest. Said member 46 consists of the rubber strip 47 which is suitably bonded with and thereby secured to the metallic backing strip 48 in a known manner. The strip 48 is preferably of thin spring metal and quite flexible so that the parts 47 and 48 of said member 46 comprise substantially one integral piece bendable as a unit for easy insertion into the jaw when required. It will be noted that the metallic spring strip 48 is arranged with its face substantially in contact with the inner face of the movable jaw 11 (Fig. 4). The end parts of the jaw 11 are bent into the form shown in Fig. 3 first inwardly away from the face of the jaw and then parallel thereto to form the bent ends 49 on the jaws 11 and to provide an end space or groove as 50 for the reception of the respective end parts of the member 46. To prevent the backing strip 48 from rising out of its proper position when the upper jaw 10 presses on the rubber portion 47 of the insert by the squeezing action of the jaw on the rubber strip, a short lug 51 projects inwardly

from the top edge of the jaw 11 and overhangs said strip 48 without, however, overhanging the rubber strip or interfering with the movement of the jaw 10. I have found that no means other than the lugs 45, 49 and 51 on the jaws 11 are needed to maintain the removable member 46 in its proper place in the jaw 11, and that even the lug 51 may be dispensed with if desired.

The member 46 being arranged in the lower jaw, its ends being in the spaces 50 and the metallic strip 48 being against the face of the jaw and the upper edge of said metallic strip being underneath the lug 51, the device is ready for operation. It will be noted that it is comparatively easy for unskilled persons to replace the member 46 when worn, cut or when it becomes aged and not sufficiently resilient, the spring backing 48 making the handling of the member and its manipulation a simple matter.

10 The bell-crank-lever having been moved to the dash-dot position of Fig. 1 to space the jaws 10 and 11 apart, the curler is moved to the front of the eye to arrange the eyelash between the jaws, and the finger loops 14 and 36 then pressed toward each other. The crank arm 39 is thereby rotated in a clockwise direction as viewed in Fig. 1, the end 42 pressing the lug 41 upwardly and consequently moving the arm 31 and the jaw 11 upwardly until the lower edge of the jaw 10 is imbedded in the rubber strip 47 thereby to curl the eyelash. The rubber strip yields during the last part of the movement, but if the operator exerts greater force upon the finger loops sufficient to overcome the resistance of the jaws and their frames, the jaw 10 may yield at the reduced parts 19 thereof and the frame for the jaw 11 may also yield somewhat, while the spring arms 13, and 31 may be bent somewhat toward each other. This take-up or yielding action is sufficient to prevent the eyelash from being cut or injured under excessive pressures. By separating the finger loops 14 and 36, the eyelash is released, the arm 31 being guided in its movement by the pins 32 and 33 moving in the slots 25, 25'

15 as well as by the flanges 26, 27 engaging the edges of the arm, if desired. There is no necessity for any other guiding means and hence the frame for the jaw 11 is completely free of the members 17 and 18 of the frame 12 and is not prevented from yielding relatively thereto under excess pressures.

It will be seen that I have provided a simple structure designed for economical manufacture and capable of performing the purposes intended.

55 While I have shown and described a specific embodiment of the invention, I do not intend to be understood as limiting myself thereto, but intend to claim the invention as broadly as may be permitted by the state of prior art and the scope of the appended claims.

I claim:

1. In an eyelash curler, a comparatively wide upper jaw having end parts reduced in width, frame members depending from the reduced end parts and forming an integral first frame therewith, an elongated first arm extending integrally and downwardly from the frame and having a portion extending upwardly within the frame, said arm having a pair of spaced aligned slots therein, a second frame within the first frame and including a lower jaw, a second arm extending downwardly from the second frame and in face to face relation to the first arm, guide pins secured to the second arm and passing through said slots, a yieldable member removably held by

the lower jaw and comprising a rubber strip and a metallic backing strip, a face of the backing strip being arranged in contact with the adjacent face of the lower jaw, a slotted member outstanding integrally at right angles to the second arm at an edge thereof, a bearing member outstanding integrally at substantially right angles to the first arm at a corresponding edge thereof adjacent the slotted member and longer than the slotted member, and a bell-crank-lever pivoted to the bearing member and having a bent lug inserted into the slot of the slotted member to reciprocate the arms relatively to each other.

2. In an eyelash curler, a pair of jaw frames of polygonal shape, each having a transverse jaw member, an arm extending from each of the frames, said arms being arranged in face to face relation, one of the arms having spaced slots therein, guide means for the arms comprising a pair of spaced pins on the other arm entering the slots of the slotted arm, and means for reciprocating the arms relatively to each other comprising a pair of apertured members each outstanding integrally from a corresponding edge of one of the arms and adjacent each other, and a bell-crank-lever pivoted to one of the apertured members at the aperture thereof and having a projection entering the aperture of the other member.

3. In an eyelash curler, a pair of curved cooperating jaws, an elongated arm for each jaw extending in a direction parallel to the axes of the jaws, each of said arms being integrally joined to a corresponding one of the jaws, one of said arms having a pair of spaced aligned slots therein and the other having similarly spaced pins passing through the slots, said arms being arranged in face to face relation, and means to reciprocate said arms relatively to each other to move the jaws alternately together and apart, said means comprising a bell-crank-lever pivoted to an outstanding extension of said one of the arms and terminating in a bent lug entering the slot of a slotted extension outstanding from the other arm.

4. In an eyelash curler having curved cooperating jaws, a pair of arms arranged in face to face relation, one of said arms being integrally connected to one of the jaws and the other arm being integrally connected to the other jaw, one of the arms being slotted and the other being provided with pins passing through the slots of the one arm, each of the arms having an apertured edge extension, and a bell-crank-lever pivoted to the extension of one arm and terminating in a lug entering the aperture of the other extension.

5. In an eyelash curler, a pair of jaw frames one normally within the other and each having an upper transverse jaw member, the end parts of the jaw member of the outer frame being substantially reduced in width to permit yielding of the jaw member under excessive pressure put thereupon by the other jaw member, and means for moving the members toward and from each other comprising a flat elongated arm extending from each frame, cooperating guide means on the arms, a bell-crank-lever, a support outstanding from one of the arms and extending beyond both of the arms, said lever being pivoted to the support, an apertured extension outstanding from the other arm, and a bent end on the bell-crank-lever arranged in the aperture of the extension to reciprocate said extension and said other arm on the oscillation of the lever.

6. In an eyelash curler, a pair of jaw frames one larger than the other and each having a transverse curved jaw, the jaw of the larger frame being reduced in width at its end parts, 5 there being a space around the smaller frame and between the frames whereby said frames are free of each other, means beyond the frames for guiding the frames in the relative reciprocatory movement thereof including a pair of flat extensions one on each frame, and means for relatively reciprocating the frames comprising a bell-crank-lever carried by one of the arms and having a projection outstanding laterally therefrom, and an apertured extension outstanding laterally from the other arm and receiving the projection. 10
7. In an eyelash curler, a pair of jaw frames mounted independently of each other and each including a jaw, a rubber strip backed with a metal strip inserted into one of the jaws with the 15 metal strip in contact with said one jaw, spaced bottom lugs on said one jaw to hold the strip in place, means at the upper edge of said one jaw to engage the metal strip and to prevent said strip from lifting out of the jaw, means for relatively reciprocating said frames, an extension on each of said frames, one part of the extension on one frame projecting in one direction from a point in spaced relation to the jaw thereof toward said jaw, and another part of said last-mentioned extension projecting in the opposite direction away from said last-mentioned jaw, and means on said extensions for guiding the frames in a reciprocatory straight line path. 20
8. In an eyelash curler, a pair of jaw frames 35 mounted independently of each other, an extension on one of the frames projecting beyond said one frame and also extending inwardly thereof, an extension on the other frame in face to face relation with the extension of said one frame, cooperating guide means on said extensions, means on said extensions for relatively reciprocating said frames, said other frame including a jaw having end grooves and also having spaced bottom lugs and provided with an inwardly bent portion at its upper edge, and a yieldable strip 40 inserted in the grooves of said jaw and against said lugs and underneath said projection, said strip comprising a rubber strip and a backing metal strip of spring material secured thereto, 45 said metal strip being arranged in contact with a face of the jaw.
9. In an eyelash curler, a first one-piece sheet metal arm having a pair of spaced slots therein and terminating at one end in an upper jaw and 50 at the other end in a finger loop, a second one-piece arm having an apertured lug outstanding therefrom and terminating in a cooperating lower jaw, a bell-crank-lever pivoted to an extension of the first arm and terminating at one end in a bent lug inserted into the aperture of the apertured lug and terminating at the other end in a finger loop, said arms being arranged in face to face relation, spaced guide pins on the second arm passing through the respective slots of the 55 first arm, and a metal backed rubber strip arranged in the lower jaw with the metal back thereof against a face of said jaw.
10. In an eyelash curler, an upper polygonal jaw frame surrounding an interior space therein, 60 an upper jaw forming the uppermost side of said frame, a lower polygonal jaw frame, a lower jaw forming the uppermost side of said lower frame, a rubber member removably carried by the lower jaw, bell-crank-lever means for moving one of 65 the frames relatively to the other in a rectilinear 70 75

path, and means for guiding said frames for such movement and for also supporting the lower jaw frame in the operative and inoperative positions thereof, said last-mentioned means including a slotted extension arranged at the center line of the lower side of the upper jaw frame, said extension projecting partway toward the upper part of said upper jaw frame and into the space thereof, and forming an incomplete partition therein, said extension being provided with a longitudinal slot therein, and a pin terminating at a point closely adjacent the uppermost end of said extension fixed in the lower side of the lower jaw frame and slidably mounted in said slot.

11. In an eyelash curler, an annular upper jaw frame having a fixed slotted extension projecting upwardly from the mid-point of the lowermost

part thereof partway toward the top thereof, a lower jaw frame movable vertically within the upper jaw frame, a pin on the lower jaw frame arranged in the slot of the extension, a lower substantially flat elongated arm projecting downwardly from the bottom parts of each of said frames, said arms being of greater width than thickness and arranged in face to face relation, the arm of the lower jaw frame having a recess therein, a bell-crank-lever pivoted to the arm of the upper jaw frame, and a projection on the lever entering the recess to reciprocate said frames relatively on the swinging movement of said lever, said fixed extension supporting and guiding the lower jaw frame during said reciprocation.

HERMAN BERNSTEIN.
